UNITED STATES PATENT OFFICE.

WILLIS E. BROWN, OF LORRAINE, KANSAS.

FOLDING CHICKEN-CRATE.

1,115,388.

Specification of Letters Patent. Patented Oct. 27, 1914.

Application filed February 14, 1914. Serial No. 818,816.

To all whom it may concern:

Be it known that I, WILLIS E. BROWN, a citizen of the United States, residing at Lorraine, in the county of Ellsworth and State 5 of Kansas, have invented new and useful Improvements in Folding Chicken-Crates, of which the following is a specification.

This invention relates to shipping crates, and particularly to crates for shipping 10 chickens or the like; and it has for its primary object the provision of a crate of this character in which all of the walls thereof are adapted to be folded onto one another to permit the crate to assume a relatively compact package for return shipment.

Another object of the invention is the provision of a structure of this character wherein the work of filling the crate or removing the contents thereof may be done expeditiously.

Another object of the invention is the provision of means for effectually holding the different walls of the crate normally in set up positions.

With these and other objects in view, the invention consists of certain novel features of construction, combination and arrangement of parts, as will be hereinafter described and claimed.

In the accompanying drawings:—Figure 1 is a top plan view of the crate; Fig. 2 is a side view thereof; Fig. 3 is a longitudinal section therethrough; Fig. 4 is a transverse section on the line 4—4 of Fig. 2; Fig. 5 is 35 an end view of the crate; Fig. 6 is a longitudinal section therethrough, showing the same in a folded condition; Fig. 7 is a section on line 7—7 of Fig. 6; Fig. 8 is a perspective view of one of the fastening devices.

The crate comprises a suitable bottom 1 provided preferably with foraminous side walls 2 and foraminous end walls 3, the latter having hinged connection at 4 with the 45 bottom at a point below the hinges 5 between the sides of the bottom and the adjacent lower edges of the walls 2. The said side walls 2 are provided with angular combined stops and braces 6, which engage against 50 the adjacent surfaces of the end walls 3 when the latter are folded to the positions shown in Fig. 3, thereby to limit the swinging movements of these walls to set up positions. The bottom and the side and end 55 walls are preferably made of sheet metal but may be made of any suitable material.

The closure sections 7—7 are employed for the purpose of closing the top of the crate after the latter is set up as shown in Fig. 4, and as illustrated said sections are 60 hinged at 8 to the upper edges of the side walls 2, so that they may be adjusted to overlie said side walls, as shown in Fig. 7 when the crate is knocked down or folded for return shipment. The positions of the 65 hinges 4 and 5 between the bottom 1 and the sides and ends 2 and 3 as specified is desired in order that the ends 3 may be first folded onto the bottom 1, as shown in Fig. 6, and the sides 2 then folded to overlie the ends 3, 70 while finally, the closure sections 7 are folded to the positions shown in Fig. 7, so as to directly overlie the sides 2. In this manner the sides and ends and the closure sections 75 may all assume substantially parallel positions relatively and the crate as a whole adjusted into a comparatively compact package, as will be understood.

When the walls of the crate are adjusted to the position shown in Fig. 7 I employ 80 means for holding said parts in such positions, and as illustrated this means consists of a chain 9 having branches 10, 10 that respectively extend in opposite directions over the adjacent superimposed walls of the crate. 85 The branches are provided with snap fasteners or the like 11 that are adapted to engage in keeper loops 12 which may be secured upon the sides of the bottom wall 1. When the crate is set up to the position 90 shown in Fig. 3 the snap hooks 11 may be connected in fixed hooks 13 secured to the sides 2. This arrangement is desirable in that all the walls of the crate may be substantially braced and held against being accidentally knocked down while the crate is 95 in shipment.

It is sometimes desirable to sub-divide the crate into non-communicating compartments, and for this reason I prefer to employ swinging partitions 14, which are suspended from fixed cross bars 15 of the closure sections 7—7. These partitions are provided with angular portions 16 that are adapted to be extended through a flange 17 on the intermediate cross bar 18 of the bottom 1. Said portions 16 may be then engaged by retaining pins 19, so that the partitions will be held against swinging to inactive positions.

Each closure section consists of longitudinal bars 20 and 21, end bars 22, an inter-

mediate bar 15 as hereinbefore referred to, and auxiliary angle bars 23. Two of such bars 23 are shown in the present instance, and they are respectively disposed at the 5 opposite sides of the intermediate bar 15. The bar 15 of each closure section is provided with horizontal spaced rods 24 that are arranged in parallel relation to the sides 20 and 21. These bars are fixed at 25 10 to adjacent bars 23 of the closure section and they slidably support a bar 26, as clearly illustrated in Figs. 1 and 4 of the drawings. In addition to the bars 24, the bar 26 has fixed thereto bars 27 and these bars in turn 15 are connected to a mating bar 28, the ends of the latter being slidable on rods 29 on the under sides of the bars 20 and 21. The rods 30 extend from the bar 26, and are disposed in parallel relation to the bars 27, 20 and they are provided with free ends having hooks 31 that are adapted to be engaged beneath flanges 32 formed on the end bar 22. The said flanges 32 are curved transversely throughout their length and 25 they are adapted to be engaged with cams 33 that are pivoted in brackets 34 of the end walls 3, as shown clearly in Figs. 2, 3, 5 and 8. It will thus be seen that when the hooks 31 of the rods 30 are disconnected 30 from the flange 32 that the bars are free for sliding movement upon the fixed bars 24. In addition to the described elements each closure section is provided with a slide bar 35, which is normally positioned adjacent 35 the intermediate bar 15. Said bar 35 has fixed thereto the inner ends of rods 36, which are similar to the rods 30 previously referred to. Said rods extend through a sliding bar 37 having its ends mounted on 40 the rods 29 and the bars are then extended over the adjacent end 22 of the closure section and the ends 38 of the rods are extended over the adjacent flange 32. The bars 39

between the adjacent bars 22 and 23 of the closure section form a guide for the bar 37, 45 while the rods 40 between the bar 37 and the bar 35 are associated with the adjacent portions of the rod 36 so as to define therewith a substantially foraminated surface.

From the construction described, it is 50 seen that either the bars 36 or the bars 30 hereinbefore referred to may be adjusted so that an opening is formed in the closure section by means of which the hand may be inserted into the crate when it is desired to 55 remove the contents thereof.

From the foregoing description, taken in connection with the accompanying drawings, the construction and operation of the invention will be readily understood without requiring a more extended explanation. 60

Various changes in the form, proportion and the minor details of construction may be resorted to without departing from the principle or sacrificing any of the advantages of this invention as claimed. 65

I claim:—

A crate comprising a bottom member, swinging side walls, swinging end walls, closure sections carried by said side walls 70 and hinged thereto and having portions extending over said end walls, means on the end walls having detachable connection with said extending portions, and a flexible brace normally extending between the bottom member and said side walls and adapted to be extended over said side walls when the crate is in a folded condition, and means on said bottom member for receiving the free terminals of said brace. 75

In testimony whereof I affix my signature in presence of two witnesses.

WILLIS E. BROWN.
